(57) **CLAIM**

The ornamental design for a mounting plate for mold, as shown and described.

DESCRIPTION

FIG. 1 is a perspective view of the front, top and right side of a mounting plate for mold showing my new design.

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 of FIG. 2; and,

FIG. 9 is a perspective view thereof showing the mounting plate for mold attached to a mold.

The broken lines in the drawings show portions of the mounting plate for mold and form no part of the claimed design. The broken lines immediately adjacent to the shaded surfaces define the bounds of the claimed design and form no part of the claimed design.
